Primary Examiner — Caron D Veynar*Assistant Examiner* — Katelin G Kloberg(74) *Attorney, Agent, or Firm* — Wilmer Cutler Pickering Hale and Dorr LLP(57) **CLAIM**

The ornamental design for footwear, as shown and described.

DESCRIPTION

FIG. 1 is a front perspective view of footwear;

FIG. 2 is an outer side view thereof;

FIG. 3 is an inner side view thereof;

FIG. 4 is a top view thereof;

FIG. 5 is a bottom view thereof;

FIG. 6 is a front view thereof; and,

FIG. 7 is a back view thereof.

The portions of the design shown in broken lines form no part of the claimed design.
